H. RESPRESS

VENTILATOR

Filed March 29, 1922

Patented June 2, 1925.

UNITED STATES PATENT OFFICE.

HEARD RESPES, OF NEW YORK, N. Y., ASSIGNOR, BY MESNE ASSIGNMENTS, TO
WORLDSBEST RAINSHIELD VENTILATOR COMPANY, INC., OF NEW YORK, N. Y., A
CORPORATION OF NEW YORK.

VENTILATOR.

Application filed March 29, 1923. Serial No. 547,642.

To all whom it may concern:

Be it known that I, HEARD RESPES, a citizen of the United States, and resident of the borough of Manhattan, city of New York, in the county of New York and State of New York, have invented certain new and useful Improvements in Ventilators, of which the following is a specification.

This invention relates to ventilators. The 10 object of the invention is the production of an adjustable ventilator, that can be located and secured in place in window frames or other openings of various widths. A second object is to provide a ventilator, through 15 which flows of air can be obtained, but which prevent rain, sleet, snow, insects and the like to pass therethrough.

The organization of the invention comprises a plate with openings that are protected by hoods. A screen is secured to the inner face of the plate and covers the openings therein. Extension members are slidably connected to the plate of the ventilator, to enable it to be connected to window frames 25 or other openings of various widths.

The accompanying drawings exemplify one form of the invention and in which Fig. 1 represents an inside elevation of a window frame, with the improved ventilator connected thereto, both having portions thereof broken away; Fig. 2 shows an outside elevation of the ventilator; Fig. 3 indicates a section of Fig. 1 on the line 3, 3; Fig. 4 is a section of Fig. 1 on the line 4, 4; Fig. 5 indicates an enlarged fragmentary portion of Fig. 4; and Fig. 6 shows an enlarged fragmentary portion of Fig. 3.

A fragmentary portion of a window frame is indicated with the side members 20, 40 the horizontal member 21, and the sash 22.

The ventilator comprises the outer rectangular plate 25, which has guards stamped therefrom bulging outwardly forming the ventilating openings 26 with the protecting hoods 27. The roofs of the latter are curved at their sides 28 and at their front portions 29. An opening 30 is indicated at the bottom of each hood. The openings 26 are in parallel rows, with the openings of 50 one row above the corresponding openings of the other row. The openings of one row may, however, break joints with the openings of the next adjacent row. The said openings are preferably made by pressing

out the material of the plate 25, the hoods resulting from the process of manufacture.

A horizontal U-shaped inwardly extending upper normally horizontal flange 35 and a similar U-shaped inwardly extending lower normally horizontal flange 36 are 60 formed with the plate 25 to provide holding flanges. At the opposite ends of the plate 25 are formed the similar inwardly extending U-shaped flanges 37 and 38.

A fly screen 40 is encased by a frame having at its upper and lower edges respectively the similar U-shaped flanges 41 and at its ends by the similar U-shaped flanges 43. The screen 40 is adjacent to the inner face of the plate 25 and covers the openings 26. 70 The flanges 41 bear against the inner face of the plate 25 and the flanges 43 are encased by the flanges 37 and 38.

On the opposite ends of the plate 25 are shown the similar extension members or end 75 pieces 45. Each of the members 45 has formed therewith the curved cut-out portion 47, the upper flange 48, the similar lower flange 49 and the side U shaped end flanges 50 with the openings 51. Angle shaped adjusting flanges 55 extend from the members 45. The said members 45 are slideable and spaced from the fly screen 40 to prevent them contacting therewith. The flange 48 engages the flange 35 and the 80 flange 49 engages the flange 36.

To use the ventilator it is located in a window frame or other opening and if in the former above or below a sash thereof.

The extension members 45 are located 85 with their end flanges 50 bearing against the adjacent side members of the window frame or other opening and fastened thereto by screws or nails, extending through the openings 51 of the flanges 50.

Various modifications may be made in the invention and the present exemplification is to be taken as illustrative and not limitative thereof.

Having described my invention what I 95 desire to secure by Letters Patent and claim is:

A ventilator comprising a plate having guards stamped therefrom and bulging outwardly producing ventilating openings, said plate being provided at its ends with extensions integral therewith bent laterally and inwardly to provide holding flanges, a 100

frame arranged upon the inner side of the plate and carrying a fly screen, said frame having its ends held within the holding flanges, guide flanges formed integral with the top and bottom of the plate, and end pieces having slid able engagement with said guide flanges and being adjustable longitudinally of said plate, said end pieces being spaced from the fly screen by the inwardly bent portions of the holding flanges

which serve to keep the end pieces from contacting with the fly screen and thereby protect said fly screen from being scraped when the end pieces are being adjusted.

Signed at the borough of Manhattan, city 15 of New York, in the county of New York and State of New York this 9th day of March A. D. 1922.

HEARD RESPRESS.
